UNITED STATES PATENT OFFICE.

JOSEPH D. PHILLIPS, OF MISSOULA, MONTANA.

BEDCLOTHES HOLDER.

Application filed August 14, 1922. Serial No. 581,730.

To all whom it may concern:

Be it known that I, JOSEPH D. PHILLIPS, a citizen of the United States, residing at Missoula, in the county of Missoula and 5 State of Montana, have invented new and useful Improvements in Bedclothes Holders, of which the following is a specification.

This invention relates generally to fastening devices and has particular relation to 10 means for fastening and holding bed clothes in position upon a bed.

An object of the present invention is 15 the provision of simple, cheap and efficient means for so holding the bed clothes, that a child or other restless person cannot disarrange the covering and thus expose themselves to the danger of colds.

Another object of the invention is the 20 provision of means as above stated, which may be adjusted in position and afterward disconnected to permit of the bed clothes being rolled back and again connected, without disturbing the adjustment.

25 With the above and other objects in view, the invention further includes the following novel features and details of construction, to be hereinafter more fully described, illustrated in the accompanying drawings and pointed out in the appended claim.

In the drawings:—

Referring in detail to the drawings, wherein like characters of reference denote corresponding parts, the reference character 45 10 indicates a portion of a bedstead and 11 the bed covering or clothes which are held in place by the improved clothes holder.

As shown in the drawings, two of these 50 holders are usually provided, one being attached to each side of the bed covering at a point slightly spaced from the top edge thereof. These holders each comprise an attaching member, herein shown in the form of a relatively large safety pin 12, which 55 is provided with an eye 13 and a shield 13', which receives the end of the pin. Detachably engaged with the eye 12' is a connecting link in the form of a snap hook 14, the said hook being provided at one end with a loop 15 through which is passed one end of an elastic strap 16, the latter being secured within the loop as shown. Secured to the strap adjacent the loop 15 is a buckle 17, which is designed to engage 60 65 the free end of the strap when the device is in use.

In the use of the invention, one of the safety pins is secured to the bed covering upon opposite sides thereof, as previously 70 stated and the elastic strap 16 is passed downward around the side rail of the bedstead 10, or around any other convenient member, such as the frame of the bed springs. The free end of the strap is then 75 secured by the buckle 17 so that the said strap is formed into a loop of proper length to permit of free movement of a person within the bed without discomfort or inconvenience. After the holders have been 80 properly adjusted, when it is desired to roll or lay back the bed covering, the snap hook may be disconnected from the eye 13 and again connected without disturbing the adjustment of the strap. This renders the device 85 exceedingly convenient in use as it eliminates readjustment of the same when a person is retiring.

The invention is susceptible of various 90 changes in its form, proportions and minor details of construction and the right is herein reserved to make such changes as properly fall within the scope of the appended claim.

Having described the invention what is 95 claimed is:—

A bed clothes holder of the character described comprising a safety pin provided with an eye at an intermediate point of the length of one of its body members, said eye being an integral part thereof, a snap hook having detachable engagement with said eye and provided with a loop at the heel of said snap hook, and an elastic strap 100 passing through said loop and provided with an adjustable bed-engaging loop. 105

In testimony whereof I affix my signature.

JOSEPH D. PHILLIPS.
